(57) **CLAIM**

The ornamental design for a toy building brick, as shown and described.

DESCRIPTION

FIG. 1 is a top front isometric view of a toy building brick showing my new design, a bottom rear isometric view being a mirror image thereof;

FIG. 2 is a right side view of the toy building brick, a left side, front side and rear side each being mirror images thereof;

FIG. 3 is a bottom view of the toy building brick, a top view being a mirror image thereof; and,

FIG. 4 is a cross-sectional view of the toy building brick taken along line 4-4 to show a depth of openings into the toy building brick.

1 Claim, 3 Drawing Sheets**FIG. 1**

FIG. 2

FIG. 3

FIG. 4
